Primary Examiner — Bao-Yen T Nguyen*Assistant Examiner* — Emily Anna Saunders(74) *Attorney, Agent, or Firm* — Greenberg Traurig, LLP(57) **CLAIM**

The ornamental design for a play gym as shown and described.

DESCRIPTION

FIG. 1 is a perspective view of the play gym, showing my new design;

FIG. 2 is a front plan view of the play gym;

FIG. 3 is a rear plan view of the play gym;

FIG. 4 is a left side elevation view of the play gym;

FIG. 5 is a right side elevation view of the play gym;

FIG. 6 is a top plan view of the play gym; and,

FIG. 7 is a bottom plan view of the play gym.

The broken lines shown in the drawings depict portion of the play gym that form no part of the claimed design. The surface shading lines in the drawings show contour and not surface ornamentation.

1 Claim, 4 Drawing Sheets(56)
